SINGLE BEAM RACKS

James Berra, Haddon Heights, N. J., and James B. McGinn, Philadelphia, Pa., assignors to American Viscose Corporation, Philadelphia, Pa., a corporation of Delaware

Application April 25, 1955, Serial No. 503,662

12 Claims. (Cl. 211—13)

The present invention relates to shipping or storing racks for a single yarn filled spool or beam.

In the past, yarn beams or spools having layers of continuous yarn ends would thereupon have generally been shipped in beam racks which are designed to accommodate a plurality of yarn beams. A filled yarn beam weighs approximately 1,000 lbs. When several of these beams are placed within a multiple beam container, the whole assembly weighs several thousand pounds. This weight factor reduces the maneuverability of the racks which complicates loading and unloading operations when shipped to customer converters who use the yarn in the knitting or weaving of fabrics. The converter also finds it difficult to move the filled beam racks to desired locations for storage or use on his premises. In addition, the converter or customer may order only one yarn filled beam, in which event, a single beam will be shipped in a large rack designed to contain a plurality of beams. Both the yarn beam shipper and converter have long desired lighter and more maneuverable beam racks which can be easily handled.

It is therefore one object of our invention to provide compact, novel and improved shipping or storing racks which will accommodate a single yarn filled beam and which can be easily maneuvered.

It is a further object of our invention to provide novel and improved single yarn beam racks having novel beam locking or anchoring devices for locking a beam firmly in place within the rack.

It is still a further object of our invention to provide novel and improved single yarn beam racks which have stacking or tiering guides whereby one beam rack may be easily positioned atop another rack for storing or shipping.

Still another object of our invention is to provide novel and improved yarn beam racks having novel and improved specific locking devices for locking in place an upper beam rack positioned atop a lower rack.

Other objects and advantages will become more apparent from a study of the following description and drawings wherein:

Figure 1 is a perspective of a single yarn beam rack;

Figure 2 is an enlarged detail of the beam stops incorporated with the rack of Figure 1;

Figure 3 is an end view of a modification of the rack of Figure 1;

Figure 4 is an enlarged detail of the locking means for holding in place a beam rack as shown in Figure 4 atop a similar rack.

Figure 5 is an end view of another modification of the rack of Figure 1; and

Figure 6 is an enlarged detail of the beam locking means for the rack of Figure 5.

Briefly, our invention comprises a rectangular metal frame or rack which has locking means for holding a yarn beam firmly in place within the rack. Tiering or stacking guides are affixed to the beam racks or frames whereby one beam rack may be easily stacked atop an

2

other rack. With certain of the rack modifications, additional locking means are provided for holding in place one rack positioned atop another.

Referring now to the drawings and more particularly to Figure 1 wherein is shown a preferred embodiment of our rack for supporting a flanged yarn beam, the metal rack or frame A for supporting a filled yarn beam or spool 1 comprises vertical corner legs 4, 4, upper and lower longitudinal supports 6, 6 welded to the legs directly and also connected with the legs through struts 6', and upper and lower transverse end supports 8, 8 welded to the legs 4, 4. Cross braces 9, 9 extend between and are affixed to the lower longitudinal supports 6, 6 to strengthen the frame or rack A. Beam supporting tracks 10, 10 also extend between and are affixed to the lower longitudinal supports adjacent the ends of the supports. The tracks 10, 10 support the beam flanges 1', 1' of the yarn beam 1. Chocks 11 which have arcuate shaped faces are bolted to the back end of the tracks 10, 10 and back up or further support the beam flanges 1', 1' to correctly position the beam within the rack A. To lock the beam 1 in position within the rack A, a turnbuckle assembly 12 is pivotally secured to the chock end of each track 10, 10. The turnbuckles 12 are positioned over each end of the beam shaft 14 and when the bolts 15 are tightened against the ends of shaft 14, the beam is firmly locked in place within the rack A.

An important feature of our invention is that two or three of the racks A may be stacked one atop the other to conserve space when shipping or storing the racks. As seen in Figure 1 of the drawing, rack stacking guides or pipes 16, 16 are welded to each leg 4, 4 of the rack A and to the beam side edge of the corner plates 18, 18. The guides 16, 16 extend inwardly toward the beam 1 at an angle, preferably but not necessarily, of about 45° whereby they will not interfere with the legs of the upper rack when resting upon the corner plates 18, 18 of the lower rack. The stacking guides 16, 16 of a bottom rack A serve to guide a second beam rack A into position atop the bottom rack as will be explained. When in position the legs 4, 4 of the upper or second rack will rest upon the corner plates 18, 18 of the bottom rack. A pair of skid legs 27, 27 for the rack A are welded to the bottom of the longitudinal and transverse frame members 6, 6 and 8, 8 and to the rack legs 4, 4 forming a corner with each leg 4. When stacking one rack A atop a bottom rack A, the corners formed by the skid legs 27, 27 cooperate or contact the guides at one or the other end of the rack A to guide or center, as the top rack is being lowered, the contacted corners 18, 18 of legs 4, 4 of the rack being lowered onto the corner plates 18, 18 of the bottom rack A. The corners formed by the skid legs at the opposite end of the upper rack will necessarily follow into position onto the opposite corner plates 18, 18 of the lower rack. The angular extending skid legs 27, 27 which extend from the bottom of the longitudinal members 6, 6, of the upper frame A, fit snugly against the complementary angularly descending end portions of the upper longitudinal members 6, 6 of the bottom frame A to longitudinally lock the racks together. The guides 16, 16 also act to prevent transverse and longitudinal movement between the stacked racks.

As seen in Figures 1 and 2, beam stops 30, 30 extend through the vertical face of tracks 10, 10 near the front or open end of the tracks. The beam stops prevent the beam from rolling off the front end of the tracks 10, 10 when the turnbuckle locking assemblies 12 are removed from the ends of the beam shaft 14. As seen in Figure 2 of the drawings, the stop assembly 30 comprises a slotted and preferably cylindrical shaped casing 33 closed at one end. The open end of the casing is threaded into a lock nut 35 which nut is welded in place over a hole through

the vertical face of track 10. A spring 37 and a latch bolt 38 are positioned within the casing 33 with the free end of the spring contacting the end of the casing. A pull pin 43 extends through slot 45 of casing 33 and is threaded into a hole in the latch bolt 38. As seen in Figure 2, the slot 45 extends downwardly at its outer end whereby the pull pin 43 may be seated after the operator has pulled the pin backward to draw the latch bolt 38 back into the casing. When the pin 43 is in its seated position, the free end of the bolt is flush with the vertical face of the track 10 thus permitting the beam 1 to be rolled along the tracks 10, 10 to be removed from the rack A. The beam 1 is preferably loaded and unloaded through the front of the rack A.

A modification of the rack A of Figures 1 and 2 of the drawings is shown in Figures 3 and 4 of the drawings. The frame structure of the modified rack B is similar to that of rack A. A turnbuckle locking assembly 12 is pivotally secured to the vertical face of each track 10 at the center of the track. The turnbuckle assemblies 12 fit over the ends of the beam shaft 14 to firmly lock the beam 1 in position within the rack B. A pair of identical chocks 50, 50 which support the beam flanges 1' are also affixed to each track 10, 10 at positions whereby they will retain the beam 1 at the center of the rack A. With this arrangement, the beam 1 is firmly locked in place within the rack B. The beam 1 in this instance is loaded and unloaded through the top of the rack B.

A stacking or tiering guide in the form of an angle plate 55 is affixed to each of the two upper transverse rack end members 8, 8. The guides 55 are diagonally opposed to one another being affixed to opposite ends of the transverse members 8, 8. Braces 57, 57 extend downwardly from the transverse frame members 8, 8, at an angle and are welded directly to the bottom edge of the corner leg 4. When one of the racks B is lowered atop a bottom rack, the sloped outer surface of the angle plates 55 guide the braces 57, 57, so that the corner legs 4, 4 of the top rack B will rest directly upon the lower rack struts 59, 59 which are somewhat similar to the struts 6' of the rack of Figure 1.

To lock an upper beam rack B in place when positioned atop a similar bottom beam rack, the racks have a pair of stacking or locking devices 60 (Figures 3 and 4). One locking device 60 is affixed to each upper transverse rack end member 8 at opposite ends of the transverse members so that the devices 60 are diagonally opposed. As seen more clearly in Figure 4 of the drawing, a latch bolt 70 is slidably mounted within a supporting frame 73 affixed to the upper transverse rack end member 8. A spring 75 is positioned around the bolt 70 and is confined between the back vertical plate 76 of frame 73 and a collar 78 secured to the bolt 70. The forward movement of the collar 78 is restricted by a stop member 79 through which the bolt 70 passes and which is welded within the frame 73. The end of the bolt extending beyond the end plate 76 of frame 73 terminates in an offset or release handle H which, when pulled by the operator will draw the bolt 70 back within the frame 73. A stop pin 82 affixed to the inside of the transverse rack end member 8 retains the bolt in its withdrawn position when the handle H is swung in position behind the pin.

As seen in Figures 3 and 4, the braces 57, 57 extending downwardly from the transverse rack end members 8, 8 have holes 85, 85 drilled therethrough so that when one rack is stacked atop another, the latch bolt 70 when released will extend through the hole 85 of the brace 57 affixed to the top frame. The compressed spring 75 forces the latch bolt 70 forward when the handle H is pivoted off of the stop or retaining pin 82. With this arrangement, an upper beam rack B may be firmly locked in place atop a bottom rack B.

A further modification of the rack A is shown in Figures 5 and 6 of the drawing. As seen therein, the rack

C has longitudinal members 90, 90 which are bracket shaped, and are welded to the top of the frame legs 92, 92. The beam supporting track 10 and chock 8 arrangement are the same as that for the rack shown in Figure 1 of the drawings. A beam locking assembly 96 affixed at each end of the rack C locks the beam 1 in place within the rack. As seen more clearly in Figure 6 of the drawings, the locking assembly 96 comprises a metal plate 98 which is pivotally mounted at 99 to each upper transverse rack end member 100. The free end of the plate 98 is of arcuate shape whereby the plate rests upon and conforms with the curvature of the beam flange 1'. The plate 98 has a hole 98' drilled therethrough. A block 102 having a hole 102' cut therethrough is welded to the top surface of the plate 98 at the free end of the plate so that the holes 102' and 98' are in alignment. A threaded lock bolt 104 operates within a casing 106 which is pivotally mounted at 107 to the front end of the transverse rack member 100. The free end of the bolt 104 terminates in a short stud 109 of a smaller diameter than the threaded portion of the bolt. A nut 108 is threaded over the free end of the bolt 104 and welded in place thereupon. The nut 108 has holes drilled through its opposite faces which holes are in alignment with drilled holes in the bolt 104. A turn rod 110 is inserted through the nut 108 and the bolt 104 to rotate the bolt. To wedge or tighten the plate 98 against the beam flange, the turn rod 110 is rotated in a clockwise direction whereupon the nut 108 is pressed or wedged against the block 102 and plate 98 to firmly impress the plate upon the beam flange 1' to lock the beam in place within the rack C. The stud 109 passes into the holes 102' and 98' of the block 102 and plate 98. This operation is repeated with the locking device 96 at the opposite end of the rack C. The beam 1 is loaded and removed from the rack C through the front of the rack. With this arrangement, the beam is locked in place with the diametrically opposed chocks and locking devices applying pressure to the forward and back portions of the beam flanges.

The tiering, stacking and locking devices used with this modification are similar to those used in the rack modification shown in Figures 3 and 4 of the drawings. The release handle H' is slightly modified, and the stop pin 82' is positioned in the upright position rather than the horizontal position. A locking device 60 is mounted within each upper bracket shaped longitudinal rack members 90 at opposite extreme ends whereby the devices 60 are diagonally opposed on the rack C. The latch bolts 70 cooperate with holes 112 in the corner legs (Figure 5) to lock in place an upper rack C positioned atop a lower rack C. When the two racks are stacked, the legs 92, 92 of the top rack are supported by the bracket shaped longitudinal rack members 100, 100 of the bottom rack C.

It is to be understood that additional modifications of the beam racks disclosed above may be made without departing from the scope or spirit of my invention as defined in the appended claims.

We claim:

1. A shipping and storing rack for a flanged yarn beam or spool comprising corner legs, transverse members connecting the legs, longitudinal members connecting the legs, a pair of transversely extending, beam supporting tracks affixed to and extending between the opposed longitudinal members, means which cooperate with the rack for retaining the beam in place within the rack, and beam stacking guides affixed to the rack which guides are out of vertical alignment with the corner legs to provide slanting surfaces for contacting and guiding the corner legs of an upper rack into position atop a lower rack.
2. A shipping and storing rack for a flanged yarn beam or spool comprising corner legs, upper and lower transverse members connecting the legs, upper and lower longitudinal members connecting the legs, a pair of trans-

versely extending, beam supporting tracks affixed to and extending between the opposed bottom longitudinal members, a beam positioning chock affixed to one end of each beam supporting track, means affixed to the tracks for locking the beam in place within the rack, and stacking guides affixed to the rack which guides are out of vertical alignment with the corner legs to provide slanting surfaces for contacting and guiding the corner legs of an upper rack into position atop a lower rack.

3. A shipping and storing rack for a flanged yarn beam or spool according to claim 2 wherein the stacking guides comprise pipes which extend above the top longitudinal and transverse rack members which pipes are affixed to the rack corner legs and which extend angularly inward toward the rack center.

4. A shipping and storing rack for a flanged yarn beam or spool comprising corner legs, upper and lower transverse members connecting the legs, upper and lower longitudinal members connecting the legs, a pair of transversely extending beam supporting tracks affixed to and extending between the bottom longitudinal members, a beam positioning chock affixed to one end of each beam supporting track, means affixed to the tracks for locking the beam in place within the rack, stacking guides affixed to the rack legs for guiding an upper rack into position atop a lower rack, and a beam stop connected with each track to prevent the beam from rolling in the tracks when the locking means are removed from the beam.

5. A shipping and storing rack for a flanged yarn beam or spool according to claim 4 wherein the beam stop comprises a spring-loaded latch bolt assembly affixed to each track which bolt, when released, crosses the path defined by the track members.

6. A shipping and storing rack or frame for a flanged yarn beam or spool comprising corner legs, upper and lower transverse members connecting the legs, upper and lower longitudinal members connecting the legs, a pair of transversely extending beam supporting tracks affixed to and extending between the bottom longitudinal members, a pair of opposed chocks secured to each track at intermediate locations of each track for supporting the flanges of the yarn beam or spool, a leg brace affixed to the bottom of each rack leg, said braces being also affixed to and extending downwardly from the bottom transverse rack members, a tiering latch bolt receiving hole in each brace, and a turnbuckle assembly pivotally secured to the center portion of each track, the free end of each turnbuckle assembly being adapted for positioning over one end of a shaft for the beam for locking the beam in place within the rack.

7. A shipping and storing rack for a flanged yarn beam or spool according to claim 6 comprising a spring-loaded tiering or stacking latch bolt locking assembly affixed to the top transverse rack members which bolt, when released, passes through a latch bolt receiving hole in a brace leg of a top rack to firmly lock the top rack in position.

8. A shipping and storing rack for a flanged yarn beam

or spool according to claim 6 comprising stacking guides affixed to the top transverse rack members which guides are out of vertical alignment with the legs of the frame to provide slanting surfaces guiding the corner legs of an upper rack into position atop a lower rack.

9. A shipping and storing rack for a flanged yarn beam or spool according to claim 8 wherein the stacking guides comprise angle plates.

10. A shipping and storing rack for a flanged yarn beam or spool comprising corner legs, upper and lower transverse members connecting the legs, upper and lower longitudinal members connecting the legs, a pair of tracks affixed to and extending between the bottom longitudinal members, a beam positioning chock affixed to the back end of each beam supporting track, and beam locking means so affixed to each upper transverse rack member whereby locking pressure is applied against a point on the forward portion of each flange of the beam, when positioned within the rack, which points are diametrically opposed to those points at which the chocks contact the beam flanges.

11. A shipping and storing rack for a flanged yarn beam or spool according to claim 10 wherein the beam locking means comprises a metal plate pivotally secured at and to the center of a top transverse rack member, the free end of the plate being of arcuate shape whereby the plate rests upon and conforms to the line of curvature of the beam flange, a drilled out block welded to the top or convex surface of the plate adjacent the free end thereof, a threaded casing pivotally secured to an end of the upper transverse member which casing may be swung in position over the free end of the plate, a lock bolt threaded within the casing which bolt at its free end terminates in a guide stud of smaller diameter than the threaded portion, a nut threaded and welded in place on the end portion of the bolt, aligned drilled holes through the nut faces and the threaded portion of the lock bolt, and a turn rod extending through the drilled holes whereby when the rod is rotated and the guide stud is inserted within the drilled out hole in the block the nut clamps or presses the block and plate against the beam flange to firmly lock the beam in position within the rack.

12. A shipping and storing rack for a flanged yarn beam or spool according to claim 10 comprising a tiering or stacking latch bolt locking assembly mounted upon the top longitudinal rack members for firmly locking in place an upper rack stacked atop a lower rack.
